UNITED STATES PATENT OFFICE.

WILLIAM LEE, OF CAMBERWELL, LONDON, ENGLAND.

ADJUSTABLE HAT-LINING.

1,134,624.

Specification of Letters Patent.

Patented Apr. 6, 1915.

Application filed May 20, 1913. Serial No. 768,703.

To all whom it may concern:

Be it known that I, WILLIAM LEE, a subject of the King of Great Britain and Ireland, residing at 101 Camberwell road, Camberwell, London, England, have invented a New Adjustable Hat-Lining, of which the following is a specification, reference being had therein to the accompanying drawing.

My invention relates to an adjustable hat lining and more particularly to a lining for use in women's hats.

By my invention I aim to produce a lining of this character which may be adjusted to hats of different sizes and when the lining has been properly adjusted permit a convenient fitting and adjustment of the hat upon the head of the wearer. The lining is also constructed so as to permit adjustment of that portion thereof resting upon the coiffure so as to facilitate the fitting of the hat to the head of the wearer and adjustment of the lining to accommodate it to different ways of dressing the hair and secure the effect of a bandeau by means of a flexible lining.

The invention consists primarily in an adjustable hat lining composed of a flexible fabric crown portion having a hem formed at the base thereof, and gathered and closed at the top thereof, a rim wire mounted in said hem, and a flexible, non-elastic cord carried by said crown portion intermediate said hem and the top of the crown whereby a supplemental flexible rim engaging the coiffure is formed; and in such other novel features of construction and combination of parts as are hereinafter set forth and described and more particularly pointed out in the claims hereto appended.

Referring to the drawings:—Figure 1 is a sectional view of a hat lining embodying my invention; Fig. 2 is a view thereof in elevation, the hat to which it is applied being shown in dotted lines, and Fig. 3 is a detail view showing the rigid band and the means whereby it may be fixed at any length to which it has been adjusted.

Like letters refer to like parts throughout the several views.

In the embodiment of my invention shown in the drawings, A indicates the fabric crown portion of the lining which may be of silk, satinet or any other desired flexible fabric. One edge of this fabric has a hem formed therein, and the other edge thereof is gathered and joined in any desired man-

ner to form a continuous crown of the fabric A. Seated in the hem of the fabric crown portion A, is an expansible wire B forming a rigid rim for said crown. Carried by the fabric crown portion A intermediate the said rim and the gathered top of the said crown portion, is a flexible non-elastic cord C which so constricts the crown adjacent thereto as to form a supplemental flexible rim, the edge of which will rest upon the coiffure, which may pass through the opening within said supplemental rim, into the upper portion of the crown of the lining. To simplify the structure of the lining, I secure said cord to the fabric by means of a tuck in said fabric through which the cord is drawn. By means of this cord, the size of the opening in said supplemental rim may be quickly adjusted, thus facilitating the fitting of the lining to the head of the wearer or its adaptation to different styles of coiffures.

The tip or top of the crown A is indicated at D.

The wire rim B is provided with an S-shaped fitting B', the open portion of each device being made so as to be readily closed over the wire to form guides in which the wire may slide.

A lining made in accordance with my invention may be manufactured in standard sizes, and fitted to any hat or any head, by merely adjusting the length of the wire B when attaching the lining to the hat, or shortening or lengthening the loop of the drawing cord C after the lining is in place.

The supplemental rim formed by the cord C, will permit the hat to be set at any angle upon the head, inasmuch as the hat is suspended by means of the lining and the engagement of said rim with the coiffure. Of course hat pins must be used to hold the hat at the desired angle. The hair, however, need not be especially dressed to permit the hat to take the desired angle or have the desired fall.

It will be observed that the hat may be set at any angle and that this angle may be changed by a mere pressure of the hand without any necessity for a special lining to secure the desired angle, or a change in the adjustment of the supplemental rim to permit a change of the angle at which the hat sets.

The flexibility of the crown portion A will permit hat pins to readily pass there-

through. It is essential that the cord C be substantially non-elastic.

It is not my intention to limit the invention to the precise details of construction shown, it being apparent that such may be varied without departing from the spirit and scope of the invention.

Having described the invention what I claim as new and desire to have protected by Letters Patent is:—

1. An adjustable hat lining composed of a flexible, fabric crown portion having a gathered top and a base adapted to be connected with a hat body adjacent the rim thereof, and means adapted to constrict said crown portion intermediate said top and said base whereby a supplemental rim adapted to rest upon the coiffure is formed.

2. An adjustable hat lining composed of a flexible, fabric crown portion having a gathered top, and a base adapted to be connected with a hat body adjacent the rim thereof, and adjustable, flexible means adapted to constrict said crown portion intermediate said top and said base, whereby a supplemental rim adapted to rest upon the coiffure is formed.

3. An adjustable hat lining composed of a flexible, fabric crown portion having a gathered top and a base adapted to be connected with a hat body adjacent the rim thereof, means whereby said base may be ad-

justed to vary the size thereof, and means adapted to constrict said crown portion intermediate said top and said base, whereby a supplemental rim adapted to rest upon the coiffure is formed.

4. An adjustable hat lining composed of a flexible fabric crown portion having a hem formed at the base thereof, and gathered and closed at the top thereof, a rim wire mounted in said hem, and a flexible, non-elastic cord carried by said crown portion intermediate said hem and the top of said crown whereby a supplemental rim engaging the coiffure is formed.

5. An adjustable hat lining composed of a flexible fabric crown portion, having a hem formed at the base thereof, gathered and closed at the top thereof, and having a continuous tuck running about same intermediate said base and said top, a rim wire mounted in said hem, means whereby the length of said wire may be adjusted, and a flexible, drawing cord seated in said tuck whereby a supplemental, adjustable rim engaging the coiffure is formed.

In testimony whereof I affix my signature in presence of two witnesses.

WILLIAM LEE.
